(57) **CLAIM**

The ornamental design for an electronic photo album, as shown and described.

DESCRIPTION

FIG. 1 is a front elevational view of an electronic photo album showing my new design;

FIG. 2 is a rear elevational view thereof;

FIG. 3 is a side view, taken from the view side of FIG. 1;

FIG. 4 is a side view, taken from the right side of FIG. 1;

FIG. 5 is a top plan view thereof; and,

FIG. 6 is a bottom plan view thereof.

The broken lines are shown in the views for illustrative purposes only and form no part of the claimed design.
